INVENTOR

William M. Henderson,
BY

Walter C. Pursey.
ATTORNEY.

UNITED STATES PATENT OFFICE.

WILLIAM M. HENDERSON, OF STEELTON, PENNSYLVANIA, ASSIGNOR TO THE PENNSYLVANIA STEEL COMPANY, OF PHILADELPHIA, PENNSYLVANIA, A CORPORATION OF PENNSYLVANIA.

RAILROAD-SWITCH.

1,005,209.

Specification of Letters Patent. Patented Oct. 10, 1911.

Application filed October 2, 1907. Serial No. 395,614.

To all whom it may concern:

Be it known that I, WILLIAM M. HENDERSON, citizen of the United States, and resident of Steelton, Dauphin county, State of Pennsylvania, have invented certain new and useful Improvements in Railroad-Switches, of which the following is a full, clear, and exact description, reference being had to the accompanying drawings, of 10 which—

Figure 1 is a plan view of a portion of a split switch showing my invention applied thereto. Fig. 2 is a section on the line $v-v$, of Fig. 1. Fig. 3 is a section on the line $x-x$, of Fig. 1. Fig. 4 is a section on the line $y-y$, of Fig. 1. Fig. 5 is a section on the line $z-z$, of Fig. 1.

This invention relates to improvements in split switches, the object being to provide a 20 renewable hard metal point for the point rails of such a switch, which shall be of novel construction and of great strength.

The invention consists in removing the head of the point rail for some distance to 25 the rear of the forward end thereof, and providing, in lieu of said removed portion, a hard metal point-forming piece provided with a web portion secured to the web of the point rail.

30 In the drawings:—1 is the main or track rail of a split switch, and 2 the movable point rail, the head portion of the forward part of which is removed, as seen in Figs. 2, 3, and 4. Filling the space usually occupied by the head of the point rail, and tapering off to the point in the usual manner, is a 35 hard steel wear-piece, 3, the under side of the head portion, 4, of said piece 3 resting for a portion of its length upon and supported by the web 5 of the point rail 2. Extending downwardly from said head portion 40 of the wear piece, on the outer side of the point rail, and its lower edge resting upon and supported by the foot flange 6 of the rail 2, is a web portion, 7. This web portion 45 extends rearwardly beyond the termination, 8, (Fig. 1) of the head portion, 4, of the wear-piece, constituting an extension, 9, (Figs. 1 and 5) fitting the space between the 50 head, web and foot flange of the outer side of the point rail to the rear of said cut away portion.

On the inner side of the point rail and fitting the web thereof, is the usual strap, 10. 55 The wear-piece, point rail, web, and strap

are suitably secured together by means of bolts, 11, as seen.

By supporting and reinforcing the wear-piece by the point rail having its web and foot flanges extending entirely the length of 60 the point, it will be observed that a very strong and efficient switch point is provided; the hard-metal wear-piece, which is usually a casting, being supported by the continuous rail throughout its entire length. 65

Having thus described my invention, I claim as new and desire to secure by Letters Patent:—

1. In a railway switch, the combination with the main rail and switch rail, of a reinforcing bar secured to the side of the switch rail toward the main rail and projecting above said switch rail to form the wearing edge, substantially as described. 70

2. In a railway switch, the combination 75 with the main rail and switch rail, said switch rail having the head removed from the point portion thereof, of a reinforcing bar secured to the side of the switch rail toward the main rail and projecting above 80 said switch rail to form the wearing edge, substantially as described.

3. In a railway switch rail, the combination with the main rail and the switch rail, 85 of a removable point section secured to the side of the switch rail toward the main rail and projecting above said switch rail to form the wearing edge, substantially as described.

4. In a railway switch, the combination 90 with the main rail and switch rail, said switch rail having the head removed from the point portion thereof, of a removable point section secured to the side of the switch rail toward the main rail and projecting above 95 said switch rail to form the wearing edge, substantially as described.

5. In a railway switch, the combination with the main rail and switch rail, said switch rail having the head removed from the point portion thereof, of a removable point section secured to the side of the switch rail toward the main rail and provided with a head occupying the position of the cut away portion of the head of the switch rail and tapered to form the switch point, said removable point section having a web portion adjacent to the web of the switch rail and secured thereto, substantially as described. 100 105 110

6. In a railway switch, the combination with the main rail and switch rail, said switch rail having the head removed from the point portion thereof, of a removable point section secured to the side of the switch rail toward the main rail and provided with a head portion and a web portion only, said head portion being tapered to form the switch point and said web portion being secured to the web of the switch rail and adapted to rest upon the base of the switch rail, substantially as described.
- 10 7. In a railway switch, the combination with the main rail and a switch rail comprising a head, a web and a base portion, of a removable switch point comprising a head and web section only, the head portion projecting above the switch rail to receive the load and the web portion being secured to the web of the switch rail and seating upon the base of the switch rail, substantially as described.

In testimony whereof, I have hereunto affixed my signature.

WILLIAM M. HENDERSON.
